ANTIBROACHING GEAR OR DEVICE

Robert R. Norris, United States Marine
Corps Reserve

Application August 1, 1945, Serial No. 608,334

4 Claims. (Cl. 114—70)

(Granted under the act of March 3, 1883, as
amended April 30, 1928; 370 O. G. 757)

1

This invention relates to landing craft adapted for landing equipment and personnel on the beach without the benefit of wharves or docks, and, more particularly it relates to anti-broaching devices for such landing craft.

One type of landing boat now in use is a shallow draft boat capable of being driven far up on a shelving beach and retracted from the beach under its own power. This type of boat is provided with a wide transverse bow which is hinged transversely substantially at the plane of the floor and which may be let down on the shore to form a ramp, serving as a gang plank for the landing of men and equipment. When the ramp is lowered, the terminal edge of the ramp rests on the beach and tends to aid in holding the boat on the beach. In many cases, the holding action of the ramp is entirely inadequate, and the boat may broach or slew around suddenly as a result of the action of wind and waves.

In general, the object of this invention is to provide anchoring means for holding landing craft on the beach in position for unloading.

Another object of the invention is to provide an anti-broaching device which will hold landing craft positively and firmly on the beach without interfering with the landing of personnel and equipment.

A further object of the invention is to facilitate the landing of personnel and equipment by providing an outboard attachment for the terminal edge of bow ramps of landing craft whereby the landing craft is held on the beach without broaching.

Another object of the invention is to provide ramp attachments or devices for landing craft adapted to dig into the beach to hold the craft and restrain it from rearward and sideward movement, and adapted to release when the craft surges forward strongly and then to dig into the beach again at the most forward position.

Other objects and advantages will be apparent from the following detailed description of the invention and from the accompanying drawing, illustrating preferred embodiments of the invention, wherein:

Figure 1 is a perspective view of an illustrative anti-broaching device attached to the terminal edge of the ramp of a landing craft, and

Figure 2 is a detail view in perspective of a spade attachment differing in some respects from the spade attachments shown in Figure 1.

Referring in detail to Figure 1, the numeral 10 denotes a bow ramp of a landing craft in its lowered position. The ramp 10 is of conventional

2

structure and comprises a wide plate, hinged transversely substantially at the plane of the floor of the landing craft, and provided with cables which are secured to the end of the ramp for raising and lowering the ramp, such means (not shown) being well known in the art. The ramp 10 is provided at its terminal edge with shaft-carrying means such as bearing blocks 11, attached to the ramp 10 by bolts or by welding or other suitable means. The bearing blocks 11 are provided with bearing sleeves 12 in which shaft 13 is rotatably mounted. Rigidly mounted on the shaft 13 are a plurality of spades 14 or other suitable flukes or pointed elements adapted to dig into the beach when the ramp 10 is lowered.

A tension arm 15 is rigidly secured to the shaft 13, adjacent one end thereof, and extending in the opposite direction to spades 14 and substantially the same plane as said spades. A tension spring 16, one end of which is secured to the end of tension arm 15 and the other end of which is secured to the ramp 10, holds the tension arm 15 under suitable tension against the vertical position stop 17, and maintains the spades 14 in digging position, substantially vertical to the plane of the ramp 10, until a force is applied which tends to drive the landing craft forward strongly. The shaft 13 rotates through an angle less than 90°, depending on the strength of the spring 16, and the spades 14 fold back under the ramp 10, so that they offer slight resistance to the forward movement of the craft.

While only a portion of the structure is shown in Figure 1, it is to be understood that the aforementioned structure may extend over substantially the entire width of the end of the ramp, or duplicate structures may be provided adjacent to the corners of the ramp, leaving an intervening space between two anti-broaching devices. The spades 14 are spaced so that the restraining force is substantially the same with respect to the center line of the boat.

Referring to the modification of the spade shown in Figure 2, the numeral 18 represents a sleeve for mounting the spade 14 on shaft 13 by suitable means such as by means of a pin, a bolt or by welding. The sleeve 18 is integral with a shank 19 and the body of the spade 14. A reinforcing member 20 is provided on each side of the spade 14 to give additional strength.

In operation, the vessel can be driven under its own power up on a shelving beach to a point at which it will rest in a stable manner free from rolling. Ramp 10 is then lowered, and the spades 14 dig into the sand of the beach, anchoring the

craft so that it cannot gain sternway. A forward surge of the craft causes spades 14 to rotate to an acute angle and pull out of the sand. As soon as the surge is completed, tension spring 16 pulls the spades to a 90° position, and they again dig into the sand and anchor the craft. As the ramp is lifted to close the bow, the spades 14 are pulled out of the sand on a line with the radius of the arc defining the path of the end of the ramp, rotating on its hinged axis.

While I have illustrated and described the preferred embodiments of my invention, many modifications and variations of the invention as hereinbefore disclosed may be made without departing from the spirit and scope thereof, and therefore no limitations should be imposed except as are indicated in the appended claims.

The invention described herein may be manufactured and used by or for the Government of the United States of America for governmental purposes without the payment of any royalties thereon or therefor.

What I claim is:

1. An anti-broaching device for a landing craft with a bow ramp, comprising anchoring means adjacent the end of the bow ramp, support means attached to the end of the bow ramp and movably supporting the anchoring means for movement relative to the bow ramp, stop means between said anchoring means and said support means limiting the movement of said anchoring means.
2. An anti-broaching device for a landing craft with a bow ramp, comprising anchoring means adjacent the end of the bow ramp, stop means for maintaining said anchoring means substantially at right angles to the plane of said ramp,

5 to prevent the craft from gaining sternway, and spring means permitting the release of said anchoring means when the craft surges forward.

3. An anti-broaching device for a landing craft with a bow ramp, comprising a transverse shaft rotatably mounted adjacent the end of the bow ramp, anchoring means fixed on said shaft to limit said anchoring means to a position substantially perpendicular to the plane of said ramp when the craft attempts to gain sternway, and spring means adapted to permit the release of said anchoring means when the craft attempts to gain headway.

15 4. An anti-broaching device for a landing craft with a bow ramp, comprising a transverse shaft rotatably mounted adjacent the end of the bow ramp, spade-like anchoring means fixed on said shaft, limiting means adjacent the side of said ramp comprising a stop mounted on said ramp and an arm mounted on said shaft, said arm abutting said stop when said spades are substantially perpendicular to said ramp, and tension spring means connecting said arm and said ramp, permitting the release of said anchoring means when the craft surges forward.

20 ROBERT R. NORRIS.
